CLAIM

The ornamental design for a stabilizer for personal watercraft, as shown and described.

DESCRIPTION

FIG. 1 is a perspective view of a hydrotab adapted for use with a personal watercraft;

FIG. 2 is a bottom view thereof;

FIG. 3 is a top view thereof;

FIG. 4 is a left side view thereof;

FIG. 5 is a right side view thereof;

FIG. 6 is a rear end view thereof; and,

FIG. 7 is a front end view thereof.

The broken lines are for illustrative purposes only and form no part of the claimed design.
